CLAIM

The ornamental design for a portable communication terminal with animated graphical user interface, as shown and described.

DESCRIPTION

FIG. 1 is a front view of a portable communication terminal with animated graphical user interface showing our new design in a first state;

FIG. 2 is a front view thereof shown in a second state;

FIG. 3 is a front view thereof shown in a third state;

FIG. 4 is a left-side view thereof shown in the first state;

FIG. 5 is a left-side view thereof shown in the second state;

FIG. 6 is a left-side view thereof shown in the third state;

FIG. 7 is a right-side view thereof shown in the first state;

FIG. 8 is a right-side view thereof shown in the second state;

FIG. 9 is a right-side view thereof shown in the third state;

FIG. 10 is a rear view of a portable communication terminal with animated graphical user interface showing our new design in any of the first, second, or third states;

FIG. 11 is a top view of a portable communication terminal with animated graphical user interface showing our new design in any of the first, second, or third states; and,

FIG. 12 is a bottom view of a portable communication terminal with animated graphical user interface showing our new design in any of the first, second, or third states.

The broken lines illustrating portions of portable communication terminal with animated graphical user interface and environment structure form no part of the claimed design. The appearance of the animated user interface sequentially transitions between the images shown in FIGS. 1-3, 4-6, and 7-9, respectively. The process or period in which one image transitions to another forms no part of the claimed design.
